DESIGN FOR A COMBINED HOLDER FOR CANDLE AND FLOWERS

Kate W. Hayt, also known as Kate Barrie,
Los Angeles, Calif.

Application March 3, 1941, Serial No. 99,288

Term of patent 14 years

To all whom it may concern:

Be it known that I, Kate W. Hayt, also known as Kate Barrie, a citizen of the United States, residing at Los Angeles, in the county of Los Angeles and State of California, have invented a new, original, and ornamental Design for a Combined Holder for Candle and Flowers, of which the following is a specification, reference being had to the accompanying drawing, forming a part thereof:

Fig. 1 is a plan view of the combined holder for candle and flowers, showing my new design;

Fig. 2 is a side elevation of the same;

Fig. 3 is a fragmentary view and is a vertical section on the line 3—3 of Fig. 1, broken away.

I claim:

The ornamental design for a combined holder for candle and flowers, as shown.

KATE W. HAYT,
Also known as Kate Barrie.
